(57) **CLAIM**

The ornamental design for a fiber optic fanout kit, as shown and described.

DESCRIPTION

FIG. 1 is a front perspective view of a fiber optic fanout kit of our new design;

FIG. 2 is a front view thereof;

FIG. 3 is a rear view thereof;

FIG. 4 is a bottom view thereof;

FIG. 5 is a top view thereof;

FIG. 6 is a right view thereof;

FIG. 7 is a left view thereof;

FIG. 8 is an enlarged partial view of FIG. 4 thereof;

FIG. 9 is an enlarged partial view of FIG. 5 thereof;

FIG. 10 is an enlarged view of FIG. 6 thereof; and,

FIG. 11 is an enlarged view of FIG. 7 thereof.

The dash-dot broken lines in the drawings are included for the purpose of illustrating boundaries and form no part of the claimed design. The small dash-dash broken lines in the drawings are included for the purpose of illustrating environmental subject matter that forms no part of the claimed design. The large dash-dash broken lines in FIGS. 4-7 are included for the purpose of identifying the portions of FIGS. 4-7 shown enlarged in FIGS. 8-11, and form no part of the claimed design. The large dash-dash broken lines in FIGS. 8 and 9 are included for the purpose of identifying the boundaries of the view in FIGS. 8 and 9 and form no part of the claimed design.

1 Claim, 7 Drawing Sheets
